UNITED STATES PATENT OFFICE

118,227

DESIGN FOR A SOCK TURNER

Harry Bowman and Paul Bowman, Larned, Kans.

Application June 28, 1938, Serial No. 78,120

Term of patent 3½ years

To all whom it may concern:

Be it known that we, Harry Bowman and Paul Bowman, citizens of the United States, residing at Larned, in the county of Pawnee and State of Kansas, have invented a new, original, and ornamental Design for a Sock Turner, of which the following is a specification, reference being had to the accompanying drawing, forming part thereof.

Figure 1 is a view in side elevation of a sock turner, showing my new design.

Figure 2 is a view in front elevation thereof.

Figure 3 is a top plan view.

We claim:

The ornamental design for a sock turner, as shown,

HARRY BOWMAN.
PAUL BOWMAN.
